MULTIPLE OUTLET NOZZLE

Peter Graham MacGregor, Pequannock, N. J., assignor to Pyrene Manufacturing Company, Newark, N. J., a corporation of Delaware

Original application August 2, 1940, Serial No. 349,916. Divided and this application April 15, 1943, Serial No. 483,109

1. Claim. (Cl. 299—141)

This application is a division of my application Serial No. 349,916, filed August 2, 1940, now Patent No. 2,340,006 issued on January 25, 1944.

This invention relates to an improved form of nozzle for use in apparatus for extinguishing fires in aircraft, and more particularly in and around the motors of airplanes.

A difficult and unique problem in the art of extinguishing fires is presented by fires that occur from time to time in airplanes while the airplanes are in the air. The forward motion of a plane through the air together with the air stream produced by the propeller or propellers creates a very rapidly moving stream of air through and around the motor of a plane, especially when air cooled internal combustion motors are employed. When a fire breaks out in such a motor, this high velocity air stream, which may be moving at a rate of 100 miles an hour or more relative to the plane, furthers the combustion of the burning material by the rapid supply of oxygen to it. A fire in an airplane motor, in fact, produces a condition quite similar to that existing in a blowtorch causing extremely rapid and high temperature combustion.

Such fires are sometimes caused by breaks in oil or gasoline feed lines but are more frequently caused by oil and/or gasoline escaping from a cracked cylinder in the motor. A fire of this type is intensely hot and rapidly damages other parts of the plane, making it extremely difficult and sometimes impossible to land the plane with any degree of security. Furthermore, if the plane is not landed properly with such a fire burning, the fire may spread very rapidly, even causing an explosion of the gasoline carried by the plane. The hazard therefore is very great and the problem of extinguishing such a fire while a plane is in flight cannot be solved by the usual fire extinguishing devices.

A primary object of the present invention is to provide special nozzles which may be located at strategic points in a plane for extinguishment of fires.

Other objects and advantages of my invention will be apparent to those skilled in the art and will be explained in detail in conjunction with the description of certain embodiments of my invention illustrated in the accompanying drawings, in which—

Figure 1 is a side elevation, partly broken away and shown in section, of an airplane motor showing an arrangement of the improved nozzle in relation to the cylinders.

Figure 2 is a side elevation partly in section of

one form of the improved nozzle that may be used according to my invention for extinguishing aircraft fires.

Figures 3 and 4 are vertical sections of this nozzle, taken on the lines 3—3 and 4—4, respectively, of Figure 2.

Figure 5 is a side elevation, partly in section, of a further embodiment of my invention showing another form of the improved nozzle as applied to an airplane motor having a single row of cylinders, and

Figure 6 is a plan view on a large scale of one of the nozzles used in the motor shown in Figure 5.

Turning now to the drawings, the improved nozzle is illustrated in Figure 1 as employed in connection with one of the motors of an airplane. By reference to applicant's parent case, now Patent No. 2,340,006, the arrangement of the improved nozzle in a complete fire extinguishing system will be more fully understood. The motor illustrated in Figure 1 is of the 14 cylinder radial Pratt and Whitney "Twin Wasp" type. Such motors are usually separated into two sections, (1) the cylinders 13 and the parts that must be located adjacent thereto, and (2) the instrument controls, carburetor, oil cooling and pumping system, and the like which are enclosed in a so-called auxiliary compartment 14 disposed rearwardly of the cylinders 13 and usually separated therefrom by a partition such as shown at 15. The cylinders 13 in the forward portion of the motor are usually covered by a removable cowl 16.

It is a feature of my invention to provide means for extinguishing fires in either the forward compartment of the engine enclosed within the cowl 16 or the auxiliary compartment 14, or in both places simultaneously. To this end, I provide immediately in front of the partition 15 and surrounding the crankcase of the motor as closely as possible, a distributing pipe 18 with a plurality of nozzles 20 and 21 extending forwardly from the distributor pipe 18 to points adjacent the base of the cylinders 13. If desired the distributor pipe may be welded to or cast as an integral part of the crankcase of the motor.

In an air-cooled motor provided with a double row of cylinders 13, such as shown in Figure 1, the cylinders are usually staggered and separated from each other by curved baffle plates 19 to direct the air around the cylinders more efficiently. In such a motor, the nozzles may consist of the short nozzles 20 which extend to points just back of the second row of cylinders and adjacent the

bases thereof with the nozzles directed radially outward, and the longer nozzles 21 which extend between each pair of the baffle plates 19 to points just back of the centers of the front row of cylinders and near the bases thereof.

In order to extinguish a fire in the auxiliary compartment 14, a second distributor pipe 22 of circular or other suitable shape may be installed just back of the partition 15.

The distributor pipe 22 may be connected by a pipe 24 extending rearwardly from the motor and through the interior of the wing in which the motor is mounted to a bottle or other container for the fire extinguishing fluid, preferably located in the pilot's cabin or at some other convenient place in the fuselage of the plane. A short connecting pipe 24a may be used to join the two distributor pipes 18 and 22 for simultaneous operation of the nozzles 20, 21 and 23.

A particularly satisfactory nozzle for use in accordance with my invention is illustrated in Figures 2, 3 and 4, and consists of a tube 32 fitted with a cap 33 fixed in position on its end in any suitable manner as by threads, welding or other suitable means. A semi-circular transverse slit 34 is cut through the pipe 32 and the side of the cap 33 at a point some distance from the forward end of the cap 33 and extending in a plane at a right angle to the tube 32. The forward end of the cap 33 is provided with an internal bore 35 of substantially smaller diameter than the bore of the pipe 32, and another semi-circular transverse slit or opening 36 is cut in the forward end of the cap in an inclined plane as seen in Figs. 2 and 3. The slits or openings 34 and 36 extend only part way around the cap 33 and both may be made of substantially semi-circular shape extending around the same 180° of the surface of the cap 33. It will be apparent, of course, that the slits 34 and 36 do not have to be exactly semi-circular but may extend more or less than 180° around the surface of the cap 33.

The nozzles 20 and 21 are preferably of the construction shown in Figure 2 and are arranged to throw sprays of the fire extinguishing fluid radially outward from points just back of and near the bases of the motor cylinders. This spray of extinguisher fluid consists of sheets of the fluid thrown from the outside periphery of the nozzle at a slight angle in a forward direction through the slits 36 and sheets of the fluid thrown from the outside periphery of the nozzle at a somewhat higher velocity, because of the lower friction loss, through the rear slits 34 in a direction at right angles to air stream flowing around the motor cylinders. These double fluid sheets are subject to the effect of the rapidly moving air stream which tends to bend backward the forwardly inclined sheets of fluid from the slits 36. The two sheets of fluid from each nozzle thus serve to reinforce each other and provide a much greater effective radius from the nozzle. In this manner, the nozzles operated simultaneously are capable of throwing outwardly from the crankcase of the motor a curtain of extinguisher fluid for a considerable distance.

By placing the nozzles 20 and 21 just in back of the bases of the motor cylinders 13, the flame from any burning oil or gasoline coming around or over the cylinders or from a crack in the side wall thereof is quickly extinguished. Since the air stream is moving towards the rear of the cylinders, it has been found that the high temperature combustion takes place near the rear

edge of the cylinders. A surprising feature of my invention is that the location of the nozzles to deliver extinguisher fluid to the rear portions of the cylinders is far more effective than placing these nozzles near the front portions of the cylinders. In a high velocity air stream, the extinguisher fluid is dissipated or dispersed too much to be effective if the nozzles are placed too far forward, but the delivery of concentrated sheets of fluid to the rear portions of the cylinders cuts off the flame quickly and completely without any back flash and without requiring the use of large quantities of fluid.

The fire extinguishing system described works most efficiently with a suitable halogenated hydrocarbon as the fire extinguishing fluid. Carbon tetrachloride is readily available in large quantities and provides an excellent fire extinguishing medium. Containers may be partially filled with this liquid and pumped up to a suitable pressure. This pressure should be sufficient to allow all or most of the liquid to be expelled through the nozzles before the pressure is completely lost.

For example, it has been found that with a fire extinguishing system using 14 double nozzles of the type shown in Figures 2 to 4, and located around the motor cylinders as shown in Figure 1, a gallon or even less carbon tetrachloride held in the container under a pressure of 150 lbs. per square inch is adequate to extinguish any type of fire that may occur in or around the motor cylinders under conditions such as exist during flight of the plane. After the discharge of a gallon of the liquid, the pressure in the container will have dropped to about 40 lbs. per square inch, but such a pressure is still sufficient to produce the full radius of liquid expelled through the nozzles.

Lower initial pressures in the containers may be employed, particularly if smaller quantities of extinguisher fluid are used. It will be understood that the exact volume of fluid and the initial pressure needed will depend upon a number of factors including the number of nozzles, their size, the size of the distributing pipes, etc. Other halogenated hydrocarbons, such as methyl bromide or trichlorethylene, or other volatile halogenated hydrocarbons having fire extinguishing properties, or combinations of such halogenated hydrocarbons may be used instead of carbon tetrachloride, as will be understood by those skilled in the art.

Referring now to Figures 5 and 6 which show an arrangement particularly adapted for supplying extinguisher fluid to an air-cooled radial motor having a single row of cylinders, no specific arrangement for supplying extinguisher fluid to the auxiliary compartment is shown, it being understood that any suitable form such as those previously described or other suitable arrangements of nozzles may be used. In this case, the motor cylinders 51 are surrounded by a suitable cowling 52 and are provided around and preferably as close as possible to the crankcase of the motor with a circular distributing pipe 53 which receives extinguisher fluid under pressure from a suitable container through the pipe 54. Nozzles 55 project forwardly from the distributor ring 53 and lie against or close to the crankcase between the motor cylinders 51.

Nozzles that may be employed for this embodiment are illustrated in more detail in Figure 6, and are provided with two semi-circular slits 56 and 57 similar to the slits 36 and 34, respectively,

in the nozzles shown in Figure 2. These slits are capable of projecting approximately semi-circular discs or sheets of fire extinguisher fluid supplied to the slits through the central opening 58 in the main tube 59 of the nozzle. The slit 56 is preferably inclined somewhat to the plane of the slit 57 in a manner similar to the inclination of the slit 36 in the nozzle shown in Figure 4. Between the slits 56 and 57 is a further slit 60 made by two intersecting cuts at approximately right angles to each other in the tubular head 59a of the nozzle, thus providing an X-shaped opening through which extinguisher fluid may be projected. The slits 56, 60 and 57 are all designed to project the extinguisher fluid in the same general direction, and the nozzles 55 are preferably disposed so as to project this fluid in a general direction radially outward from the crankcase of the motor.

The nozzles are preferably arranged so that the cross-shaped slits 60 are disposed approximately on the center line of the motor cylinders 51 with the inclined slits 56 disposed a substantial distance ahead of the center line of the cylinders. With this arrangement the nozzles 55 in extinguishing a fire project a triple curtain of extinguisher fluid radially outward from points between the motor cylinders and near the bases thereof. The force of the wind stream tends to sweep this curtain of extinguisher fluid rearwardly, so that the fluid from two adjacent nozzles 55 strikes the motor cylinder between them along its rear edge, thus effectively cutting off any flame streaming from the back of the cylinder.

While the nozzles illustrated in Figures 2, 3, 4 and 6 are particularly effective in a system as shown and described herein, it will be apparent

to those skilled in the art that such nozzles may also be used effectively for other purposes.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

15 A nozzle for projecting jets of fluid comprising a tubular member having separate spaced transverse slits therein for projecting jets of fluid, and intersecting slits therebetween for projecting an additional jet of fluid.
